UNITED STATES PATENT OFFICE.

GEORGE ERTEL, OF QUINCY, ILLINOIS.

BALING-PRESS.

SPECIFICATION forming part of Letters Patent No. 349,934, dated September 28, 1886.

Application filed April 7, 1886. Serial No. 198,071. (No model.)

To all whom it may concern:

Be it known that I, GEORGE ERTEL, of Quincy, in the county of Adams and State of Illinois, have invented a new and Improved 5 Baling-Press, of which the following is a full, clear, and exact description.

My invention relates to presses adapted for baling hay, straw, and other material, and has for its object to provide a press which may be 10 fed either at the top or at one side, and may be operated when fed from the top without closing the top feed-door, and so arranged that whether the top or side door be closed prior to pressing each successive increment of material fed into the press-case either of said 15 doors may be opened automatically by the movement of the plunger.

The invention has for a further object to provide for a more effective retaining of the 20 pressed batches or charges of material when the plunger recedes from them.

The invention consists in certain novel features of construction and combinations of parts of the baling-press, all as hereinafter fully described and claimed.

Reference is to be had to the accompanying drawings, forming a part of this specification, in which similar letters of reference indicate corresponding parts in all the figures.

Figure 1 is a side elevation of my improved baling-press with the press-case, plunger, and other parts broken away and in section, and with the top feed-door open. Fig. 2 is a plan view of the press with parts broken away and 35 in section, and showing the side feed-door open. Fig. 3 is an enlarged view, in longitudinal sectional elevation, of parts of the press next to the top feed-door, which is closed, and the devices for automatically opening this 40 door by the movement of the plunger, and also of the devices for preventing rebound of the plunger. Fig. 4 is a detail broken plan view of part of the press-case and the plunger. Fig. 5 is a rear end view of the press-case 45 with part of the truck on which the case is mounted; and Fig. 6 is a view of the back end of the plunger, drawn to the same scale as in Figs. 1 and 2.

The press-case A is provided with a top feed-door, B, and a side feed-door, C, hinged at *b c*, respectively, to the top and side of the case.

The plunger D of the press is connected by a beam, *d*, yoke *d'*, head *d''*, and chain *d'''* to the sweep *d''''*, allowing a complete forward stroke 55 and return of the plunger for each half-turn of the sweep in reverse directions. This mechanism for operating the sweep is fully described in a United States patent, No. 336,305, granted to me February 16, 1886, and there- 60 fore needs no further description here.

Any suitable mechanism may be used to operate the plunger in the press-case.

The usual apron or guard, C', is fixed to the side of the press-case, and over or past which 65 material to be baled is fed into the case.

In and through the floor of the press-case, and preferably at or near the point at which the plunger D stops on its forward stroke, I make a slot, E, by dividing the longitudinally- 7c ranging bottom planking or lining of the press-case; or, in other words, the bottom planking, instead of being continuous from end to end of the press-case, is made in two sections placed some distance apart to form the slot E, 75 and so that the dust or dirt in the loose hay or other balable material being fed into the press-case either at the top or side door will fall through the slot, and the forward edge or margin of the slot will scrape the dust and dirt 80 from the under side of the material while in process of formation into a bale, and whereby the dust and dirt will not be carried forward and pressed into the bale, thus insuring cleaner bales. The slot E is, by preference, 85 formed obliquely across the bottom of the press-case, the more effectually to guard against the forcing of the material being baled through it along with the dust and dirt. It is obvious that the slot E is a very much more simple 90 contrivance allowing discharge of the dust and dirt from the press-case than is a series of rollers journaled transversely across the case in an opening of its bottom, as has heretofore been done; but these rollers are liable to clogging 95 by the dirt, and are costly to apply and keep in running order. Furthermore, the rollers cannot have the scraping effect on the bottom of the material being baled to clear it of dirt, as does the forward edge of the slot E, as above 100 described.

The forward end of the press-case is open for continuous discharge of the bales after they are tied at the open sides *a* of the case in rear

of where the bales are formed between grooved spacing-blocks of any approved kind, which it is unnecessary to show or describe.

Side pieces, A' A', are fitted into grooves in 5 the upper and lower side timbers of the press-frame, and bolts A² A², passed vertically through the side timbers, have nuts a² a², allowing the top and bottom walls, A³ A³, of the press-case to be drawn toward each other to 10 contract the open end of the press-case and offer resistance to the passage of the bales to control the density of the bales to any desired degree. (See Figs. 1, 2, and 5.)

To the free end of the top door, B, there is 15 fixed a case, b', in which is fitted to slide a bolt, F, on which, between the end of the case b' and a collar, f, on the bolt, is placed a spring, f', by which the bolt is normally forced forward, so as to automatically engage a latch- 20 plate, F', fixed to the press-case as the door closes, and as shown in Fig. 3.

To a bracket or arm, B', fixed to the door B, is attached one end of a rod, B², the other end of which is connected to a rod, G, which 25 passes through a metal tube, G', fixed to the press-case, and preferably to a flooring or platform, a', on the case. The rod G has a fixed collar, g, between which and the end of the tube G' is placed around the rod and in the 30 tube a spiral spring, H, which tends normally to expand and raise or open the door B when it is unlatched automatically by the back movement of the plunger, as next described.

A chain, I, connected at one end to the latch-bolt F, extends along the press-case over the 35 platform a', which supports the chain, and the other end of the chain is attached to the upper end of a lever, I', which is pivoted on a cross-rod, i, held to the case A, and to the lower 40 end of lever I' is connected one end of a rod, J, which extends rearward at the inside of the press-case over the plunger-operating mechanism and passes loosely through a hole in the upturned flange k of a plate, K, fixed to the 45 top of the plunger near its back end. The end of the rod J is screw-threaded to receive a stop-nut, j, which may be set on the rod to cause the contact of the flange k with the nut about at the time the plunger reaches the limit 50 of its inward stroke, to cause the rod J to draw on lever I', and through it on the chain I, to draw the bolt F and allow the spring H to draw the door B open, as in Fig. 1, to permit the next charge of material to be fed through 55 the top doorway in front of the plunger when the latter is moved outward or backward in the press-case to the position shown in Figs. 2 and 3 of the drawings.

When the press is not in use, or when the 60 side door, C, is to be operated for feeding the press at the side, as on a windy day, and when the top door, B, will be closed, the rods B² G will be disconnected, to allow the spring H to freely expand, and thereby retain its elasticity.

When the press is to be fed at the side, a 65 short chain, c, will be hooked at one end into a staple or eyebolt, c', fixed to the plunger D,

and the other end of this chain c will be attached to one arm of an elbow-lever, L, pivoted to the press frame or case. A chain, c², 70 connects the other arm of lever L with the stem of a forked bolt, M, on the door C, and whereby when the plunger moves outward the door C will be opened automatically to allow the next charge of material to be fed into the 75 press-case in front of the plunger.

It is evident that either a top or side feed may be given the press at the will of the operator, and that whether the top or side door be used it will be opened automatically by the 80 movement of the plunger; but both doors will be closed by hand, except when it may be desired to feed the press from the top and press the bales without closing the top door, as may be desirable at times—in baling straw, for instance, when the smoothness of the bales is not of great importance, and as will be hereinafter explained.

In presses of this character, or wherein the plunger is forced outward more or less violently by the expansion of the charge of material last pressed when the outer end of the plunger-beam passes the center, an effective 90 brake device to prevent rebound of the plunger and shock to the plunger-operating mechanism and press-case is desirable. I construct such a brake device as follows: A brake-lever, N, is hung in an opening at the top of the press-case by means of a headed bolt, n, which passes freely through a cross-timber, O, which is 95 bolted at o o to the top of the case. A spring, n', placed between the head of bolt n and the top of the brake-lever, draws the lever up toward the timber O, but allows the lever to be forced downward by impact against it, or 100 against a metal plate, n², on it, of the end of a screw-shaft, P, which is threaded into a nut, p', embedded in the cross-timber a³ of the press-frame, and has a bent upper end, p, by which it may be turned up or down to adjust 105 the brake-lever bodily in horizontal plane, for purposes presently explained. To the under side of the outer end of the brake-lever N there is fixed an inclined block, N', which is 110 adapted to be struck by an inclined block, D', on the top of the plunger D, and to the under side of the opposite end of the lever N there is fixed a metal plate or shoe, N², which is 115 adapted to press upon a metal plate, D², fixed to the top of the plunger. A cleat or block, 120 n³, fixed to the press-case over the end of the lever N, prevents an undue drawing up of that end of the lever by the spring n'. It thus will appear that the brake-lever N is 125 yieldingly supported in the press-case, and that by screwing the shaft P downward the inclined block N' will be lowered, so that the corresponding block, D', on the plunger will strike it just about the time the back or outer end of the plunger strikes the rubber buffers 130 R, fixed to cross-bars of the press-frame, or, in other words, when the plunger reaches the limit of its back-stroke. This contact of the blocks D' N' causes the opposite end of

the brake-lever N to be suddenly thrown downward on the end of the screw-shaft P as a fulcrum, and whereby the plate N² on the lever is carried forcibly against the plate D² on the 5 plunger, and the brake-lever will simultaneously adjust itself with about equal pressures on the block and plate D' D² of the plunger, and prevent a rebounding forward movement of the plunger until the plunger-beam d is 10 again moved to give the next outward stroke to the plunger, and the instant the inclined block D' is carried from under the brake-lever block N' the lever will release its hold on the plunger. It is evident that by adjusting the 15 screw-shaft P the brake-lever N may be set accurately to clamp the plunger when the press is first made, and also may be adjusted as the plunger and press-case wear by use. Consequently the plunger may at all times be 20 stopped by the brake-lever acting with any amount of force which the operator may in practice find most preferable to give the best results in preventing rebound of the plunger and shocks to the press.

25 Across the rear end of the top feed-opening of the press there is pivoted on a suitable pin or bolt, S, a metal casting, T, which I call a "retainer," and which extends across the full width of the press-case opening or box 30 in which the plunger D works. (See Figs. 1, 3, and 4.) This retainer is provided with a heavy lip or flange, t, which extends the full length of the retainer, and by its weight causes the retainer to normally turn on the 35 pivot S to the position shown in full lines in Fig. 3, without the aid of springs, and until a lip or stop-lugs, t', on the retainer strike a projecting lip or flange, a⁴, on the press-case A, at which time the rear side or face of the 40 retainer-lip t stands about vertically. The press-case just beneath the stop-flange a⁴ is cut away, as at a⁵, to allow the lip t of the retainer T to turn up into said recess, as in full lines in Fig. 1, and in dotted lines in Fig. 3, 45 as the plunger moves toward the limit of its outward stroke, and the top of the plunger at its pressing end is cut away, as at U, to allow some of the hay, straw, or other material being baled to pass between the turned-up retainer- 50 lip t and the top of the plunger, as the latter approaches and reaches the limit of its outward stroke.

The operation of the retainer T, in connection with the plunger, is as follows: Should 55 the door B be closed down on the charge of material fed at the top of the press-case in front of the plunger, as the plunger advances to press the material the lip t of the retainer T will be turned upward nearly to horizontal position, and a reasonable amount of the material may without overstrain or excessive friction 60 of the parts be carried into the recess U of the plunger beneath the upturned lip t of the retainer, and as the plunger moves outward 65 again and the material expands when released from the heavy pressure of the plunger the extremity of the lip t will be caught by the

expanding material, and will be turned down thereby as the retainer turns bodily on its pivot S, until the stop t' strikes the press-case lip 70 a⁴, whereupon further expansion of the pressed material at the top of the press-case will be checked, and the retainer T thus will coact with the ordinary spring-pressed retaining-hooks, V, fitted, preferably, three at each side of the press-case, in holding the pressed material until the next charge shall have been fed into the case and pressed by the plunger. The retainer T will act in the same way to prevent undue expansion of the pressed material at the top of 80 the press-case, whether the press be fed at the top opening, as above described, or at the side opening; but the most important office of the retainer, and particularly in connection with the plunger recessed at U, as above described, is to allow the press to be operated when fed at the top without closing the top door, B, upon each successive increment of material fed into the press-case, and which mode of operating the press may at times be 85 preferred when baling straw or other material, and when the smoothness of the bales at the upper side is not of prime importance, and when operating the press in this way it is obvious that the lip t of the retainer T will 90 yield or turn up as the end of the plunger moves beneath it, and as the end of the plunger moves but a short distance past the retainer T the material being pressed would not bind excessively hard between the retainer 95 and the plunger, even if the plunger were not recessed at U; but by so recessing the plunger all danger of excessive binding and friction of the material is avoided.

By constructing the baling-press in the manner above described, allowing the press to be fed either at the top or side, and by providing for interchangeable connection of the latch devices to the plunger for opening either the top or side door automatically by the movement 100 of the plunger, and also by providing the retainer T in the press case, I produce a press having a very wide range of usefulness, both as regards the material to be baled and the preferred manner of operating the press in 105 baling it.

Having thus fully described my invention, I claim as new and desire to secure by Letters Patent—

1. A baling-press comprising a case, a plunger operating therein, top and side feed-doors provided with latch devices, and connections from said latch devices adapted for alternate attachment to the plunger, substantially as shown and described, whereby either the top 110 or side feed-door may be unlatched for opening by the movement of the plunger, as set forth.

2. A baling-press having its bottom plank- 115 ing or lining made in two sections spaced apart to provide a dust-exit slot, as at E, at the bottom of the feed-opening of the press-case, sub- 125 stantially as described, for the purposes set forth.

3. In a baling-press, the combination, with the press-case and a top feed-door, as at B, hinged thereto, of a tube, G', fixed to the case, a spring, as at H, fitted in the tube, and connections from the back end of the spring to the door, substantially as shown and described, whereby the spring will be put in tension by the closing of the door, and will automatically open the door when said door is unlatched, as to set forth.

4. In a baling-press, the combination, with the press-case having a top feed-opening and a door, B, hinged thereat, of rods B² G, a tube, G', into which rod G passes, and a spring, as at H, fitted in the tube between one end of it and a shoulder on the rod G, substantially as herein set forth.

5. In a baling press, the combination, with the press-case having a top feed-opening, a door, B, hinged thereat, a latch, as at F, on the door, adapted to engage a catch-plate on the press-case, and a plunger working in the case, of a chain, I, lever I', and a rod, J, connected to the lever I' and to the plunger, substantially as shown and described.

6. In a baling-press, the combination, with the press-case having a top feed-opening, a door, B, hinged thereat, a latch, as at F, on the door, adapted to engage a plate on the press-case, and a plunger working in the case, of a chain, I, lever I', rod J, a plate, as at K, on the plunger, and a stop or nut, j, on the rod J, substantially as described, for the purpose set forth.

7. In a baling-press, the combination, with the press-case and a plunger operating therein, of a brake-lever, as at N, hung so as to be adjustable vertically at the top of the press-case, and adapted to clamp the plunger automatically about at the limit of the back-stroke of the plunger, and a vertically-movable fulcrum pin or shaft, as at P, fitted in the press-case and bearing on the brake-lever and adapted to adjust it bodily to the plunger, substantially as described, for the purpose set forth.

8. In a baling-press, the combination, with the press-case and a plunger operating there-

in, of a brake-lever, N, hung at the top of the press-case by a pin or bolt, n, and a spring, n', 50 and adapted to clamp the plunger automatically about at the limit of the back-stroke of the plunger, and a vertically-movable fulcrum pin or shaft, as at P, fitted in the press-case and bearing on the lever and adapted to adjust it bodily to the plunger, substantially as herein set forth.

9. In a baling-press, the combination, with the press-case and a plunger operating therein, of a brake-lever, N, held to the case and 60 provided with an inclined clamp-block, N', and a correspondingly-inclined block, D', on the plunger, substantially as herein set forth.

10. In a baling-press, the combination, with the press-case and a plunger operating therein, of a brake-lever, N, hung at the top of the case by a pin or bolt, n, and a spring, n', a vertically-movable fulcrum pin or shaft, as at P, fitted in the press-case and bearing on the lever and adapted to adjust it bodily to the 70 plunger, and inclined blocks N' D' on the brake-lever and plunger, respectively, substantially as herein set forth.

11. In a baling-press, the combination, with the press-case and a plunger operating therein, of a brake-lever, N, hung at the top of the case and provided with inclined and flat clamp-plates N' N'', a vertically-movable fulcrum pin or shaft, as at P, fitted in the press-case and bearing on the lever, and inclined and 80 flat clamp-plates D' D'', fixed to the plunger, substantially as herein set forth.

12. In a baling-press, the combination, with the press-case and a plunger operating therein, of a retainer, T, formed with a pendent 85 lip, t, and stop t', and pivoted, as at S, at the rear end of a top feed-opening of the press-case, and said case cut away at a⁵ to receive the lip t, and having a stop flange or lip, a⁴, which the retainer-stop t' is adapted to strike, 90 substantially as herein set forth.

GEORGE ERTEL.
